(57) **CLAIM**

The ornamental design for a breast pump bra with zipper, as shown and described.

DESCRIPTION

FIG. 1 is a perspective view of a breast pump bra with zipper showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front view thereof, shown the state of zipper opened.

FIG. 9 is another front view thereof, shown the state of zipper opened.

FIG. 10 is a front view thereof, shown another type of a breast pump bra with zipper; and,

FIG. 11 is a front view thereof, shown another type of a breast pump bra with zipper.

The broken lines in the drawings depict portions of the breast pump bra with zipper that form no part of the claimed design.
